UNITED STATES PATENT OFFICE

2,482,534

ENGINE STARTING APPARATUS

John E. Antonidis, Anderson, Ind., assignor to
 General Motors Corporation, Detroit, Mich., a
 corporation of Delaware

Application July 2, 1948, Serial No. 36,636

3 Claims. (Cl. 74—7)

1

This invention relates to electrical engine starting apparatus of the type which includes a pinion connecting with the shaft of the starting motor and movable therealong into mesh with the engine flywheel gear and which includes an electromagnet which operates through a spring to shift the pinion and which closes the starting motor switch, the spring yielding in case of abutment of the pinion with the engine gear to permit closing of the switch by the electromagnet so that the motor can operate to release the abutment whereupon the spring is released quickly to move the pinion into mesh with the engine gear. Electromagnets or solenoids for this purpose are disclosed in Dyer Patent 2,287,791 and Claytor Patent 2,318,672.

An object of the present invention is to reduce the cost of the solenoid. I have found that it is possible to use a solenoid of smaller dimensions and requiring less magnet wire by a construction which provides in case the pinion abuts the engine gear, that the force then opposing further movement of the solenoid armature is applied axially of the armature and not obliquely thereby minimizing the force required to overcome friction and making possible the use of substantially all of the magnetic force to start deflection of the spring. As the spring is deflected by movement of the armature toward a fixed core, the opposing force becomes slightly oblique and the friction between the armature and its guide increases. The total opposing force increases also with deflection of the spring but the magnetic pull increases at a faster rate because the gap between the armature and core decreases.

Another object is to provide for adjustment of the distance through which the pinion is moved by the solenoid armature from normal demeshed position in order to compensate for variations in the relation between the flywheel gear and the flywheel housing to which the starting apparatus is attached. This object is accomplished by providing for the attachment of the solenoid housing to the motor field frame by means which permits adjustment of the former relative to the latter.

A further object is to prevent the entrance of dirt and moisture into the guide bearing provided by the solenoid housing for supporting the solenoid armature for axial movement. This is accomplished by the use of a flexible rubber boot connected with the housing and armature and enclosing the portion of the armature exterior to the housing, said boot permitting the adjustment mentioned in the preceding paragraph.

Further objects and advantages of the present

2

invention will be apparent from the following description, reference being had to the accompanying drawings, wherein a preferred embodiment of the present invention is clearly shown.

5 In the drawings:

Fig. 1 is a side view, partly in longitudinal section, of engine starting apparatus embodying the present invention.

Fig. 1A is a fragmentary view in the direction of arrow 1A of Fig. 1.

Fig. 2 is a longitudinal, sectional view of the solenoid.

Fig. 2A is a sectional view on line 2A—2A of Fig. 2.

10 Fig. 3 is a view in the direction of arrow 3 of Fig. 2.

Fig. 4 is a sectional view on line 4—4 of Fig. 3.

Fig. 5 is a sectional view on line 5—5 of Fig. 2.

Fig. 5A is a sectional view on line 5A—5A of Fig. 5.

15 Fig. 6 is a view in the direction of arrow 6 of Fig. 2.

Fig. 7 is a fragmentary, sectional view of solenoid and a boot for protecting the solenoid armature.

20 Fig. 8 is a view similar to Fig. 7, showing the boot compressed.

Fig. 9 is an end view of the boot.

Fig. 10 is an end view of shell 66 and plate 30 60 modified to retain the boot.

Fig. 11 is a view in the direction of arrow 11 of Fig. 7, lever 41 being omitted.

Fig. 12 is a longitudinal, sectional view of link 47.

35 Referring to Fig. 1, a frame 20, adapted to be attached to the housing (not shown) of an engine flywheel gear 21, supports the field frame 22 of starting motor M, said frame 22 supporting an end plate 23 and enclosing a motor armature 24 on a shaft 25 journaled in bearings 26 and 27 provided by the plate 23 and frame 20 respectively. Shaft 25 has splines 28 engaging splines of a sleeve 29 connected with the driving member 30 of a one-way or overrunning clutch having rollers 31 through which torque is transmitted in one direction by the driving member 30 to a driven member 32 connected with a pinion 33 adapted to mesh with the gear 21 but normally out of engagement therewith. A collar 34 made of two parts welded together is slidable on the sleeve 29 and is retained by a split-wire snap ring 35. A spring 36 is retained under initial compression between the collar and the clutch. For further details of the starter drive, reference is made to Critchfield Patent 2,211,053.

55 Frame 20 supports a pivot screw 40 for the hub

41h of a lever **41** made of two parts spot-welded at **43** so that its lower portion is bifurcated to provide two arms **41a**, each carrying a stud **42** received between the flanges of collar **34**. A spring **41s** is coiled around the lever hub **41h** and has an end **41f** pressing the direction of arrow **x** on frame **20** and an end **41w** pressing the direction of arrow **y** on lever **41**. Spring **41s** urges lever **41** clockwise. Counterclockwise movement of the lever **41** effects movement of the pinion **33** toward the gear **21**. Lever **41** has a slot **44** for receiving a pin **45** extending across the arms **46** of a U-shaped link **47**, said arms extending through slots **48** in a plate **49** which retains the yoke of the link. Plate **49** is attached to the armature **51** of a solenoid unit **50** which will now be described.

Armature **51** is guided by a non-magnetizable metal tube **52** which surrounds a core **53** and which is surrounded by a magnet coil **54** of relatively coarse wire and a magnet coil **55** of relatively fine wire which are surrounded by an inner shell **56** abutting plates **57** and **58** abutting plates **59** and **60** respectively, the latter having a flange **61** surrounding the tube **52**.

Tube **52**, plate **58**, insulating washers **62** and **63** and metal washer **64** are assembled to provide a spool on which the coils **54** and **55** are wound.

Core **53** and plates **57** and **59** are united by projection welding.

Link **47**, plate **49** and armature **51** are united by forcing the plate **49** into a counterbored recess **51a** of the armature after the link arms **46** have been passed through the holes **48** in the plate. Recess **51b** of the armature provides for limited swinging movement of the link **47**.

The inner shell **56** and its enclosing outer shell **66** are made by cylindrically forming sheet metal pieces. The joints or seams are not united. The joint of shell **56** and the joint of shell **66** are at the top and bottom, respectively, in Fig. 2. While these shells are squeezed together sufficiently to obtain the required inside diameters thereof, a bracket **67** is spot-welded to the outer shell. Bracket **67** has flanges **67f** curved to fit the motor field frame **22** and these flanges provide four longitudinally extending slots **68** for receiving screws **69** for attaching the bracket to the field frame in the position required as will be explained later.

To the plate **60** there is assembled a felt oil impregnated seal ring **70** and a ring retainer **70a**. Ring **70** engages the armature **51** to exclude dirt and moisture.

The winding assembly (parts **52**, **58**, **62**, **63**, **64**, **54** and **55**), the core assembly (parts **53**, **57**, **59**), and the plate **60** are assembled within the shell assembly (parts **56**, **66**, **67**) and the edges of shell **66** are formed at **66a** against the plates **59** and **60** to retain the parts in assembly.

Screws **71a** (Fig. 3) attach a bracket **71** to the plate **51**. Bracket **71** insulatingly supports a terminal screw **72** to which one end each of coils **54** and **55** are connected; and terminal **72** is connected by a push button switch **5** (Fig. 1) with the non-grounded terminal of the storage battery **B**. Bracket **71** insulatingly supports screws **73** and **74** the heads of which provide stationary switch contacts **75** and **76** respectively which are located so as to be bridged by a metal disc **77** (Figs. 2 and 5) which surrounds a rod **79** and is located between two non-conducting washers **77a** and **78** supported by the rod **79**. Washer **77a** has notches **77b** which receive projection **77c** of disc **77** (Figs. 5 and 5A). Rod **79** is guided for longitudinal movement by the core **53**. A spring retainer cup **80** supported by bracket **71** receives a

spring **81** which surrounds the left end of rod **79** and which bears against a cupped C-washer **82** received by a groove in rod **79** (Fig. 2A) and which retains the washer **82**. A second cupped C-washer **83** is received by a groove **84** in rod **79** and is engaged by a spring **85**, which retains the washer **83** and which bears against a washer **86** which bears against the washer **77a** and urges it against the disc **77** and the latter against the washer **82**. Spring **81** urges the contact disc **77** away from the contacts **75** and **76** and the washer **83** against the plate **57**.

Terminal screw **73** is connected with the non-grounded terminal of battery **B** (Fig. 1) and the screw **74** with the insulated terminal **T** of the starting motor **M** whose other terminal is grounded. Screw **74** is connected with the end of the coil **54** not connected with the terminal screw **72**. The end of coil **55** not connected with the screw **72** is grounded. A cover **90** which is attached by a screw **91** to the bracket **71** has holes for receiving the screws **73**, **74** and the retainer **80**.

To start the engine, the push button switch **S** is closed to connect both coils **54**, **55** with the battery **B**. The armature **51** moves left to cause the pinion **33** to move right (Fig. 1) into mesh with the gear **21** and to cause the rod **79** to move left to act through spring **85** to press the disc **77** against the contacts **75**, **76** whereupon the starting motor **M** receives current from the battery **B** and the coil **54** is short circuited. The coil **55** is operative to maintain the armature **51** in its leftmost position. The starting motor **M** cranks the engine to render it self-operative. When the engine is self-operative, the switch **S** is released and spring **41s** moves the lever **41** clockwise and starter drive to the left and against a stop sleeve **25a** on shaft **25** thereby demeshing the pinion **33**.

In case the ends of the pinion teeth abut the ends of the flywheel gear teeth, the solenoid armature **51** will compress the spring **36** and move the contact disc **77** into engagement with the contacts **75**—**76**. The motor turns the pinion **33** into meshing registration with the gear **21** whereupon the spring **36** is released quickly to move the pinion **33** into driving engagement with the gear. When the pinion is in gear abutting position **33'** (Fig. 1) lever **41** will be in position **41'** represented by dot-dash lines and link **46** will be in position **46'** and the right end of armature **51** will be at **51'**. Therefore when the armature **51'** begins its compression of spring **36** by movement to the left of position **51'** the force opposing magnetic pull will be axial with respect to the armature **51** and the frictional resistance between the armature and its guide **52** will be practically negligible. Therefore when the gap between the armature **51** and the core **53** is relatively wide, the magnetic force is practically unopposed by friction between the armature and its guide. As the armature **51** moves to the left of position **51'**, the air gap decreases and magnetic pull increases at a rate faster than the rate of increase of opposing forces due to deflection of springs **36** and **41s** and friction between the armature and its guide. By the use of a construction which results in minimum frictional resistance between the armature and its guide when the pinion begins abutting the flywheel gear, the coils **54** and **55** can be made smaller than required if frictional resistance under the same condition were substantial. A reduction in ampere turns of these coils results in reduction in mechanical dimension and therefore reduction in cost of manufacture.

As described in Patent 2,302,687, the slot **44** in

lever 41 provides a lost motion connection which permits opening of the starter switch by separation of contact 71 from contacts 75 and 76 upon release of the control switch S although the spring 41s will be unable to move the pinion 33 out of mesh with the gear 21 due to friction between these parts which could occur in case the motor is unable to rotate the engine gear after the pinion has been fully meshed therewith.

Due to slight variations in manufacture of engines, the relation of the flywheel gear to that surface of the flywheel housing to which the frame 20 is attached, is not exactly uniform. In order that the pinion 33 can be fully meshed with the gear 21 without touching the washer 25b which abuts a surface of the frame 20, it is necessary to provide for adjustment of the distance through which the pinion is moved from demeshed to fully meshed position by the solenoid armature 51. Since left movement of the armature 51 is stopped by additional compression of springs 85 and 81, the distance through which the armature 51 and hence the pinion 33 moves is determined by the location of the solenoid bracket 67 relative to the motor field frame 22. To make the adjustment, the screws 69 are loosened and the bracket 67 and the solenoid parts supported thereby are moved along the frame to the required position; and the bracket 67 is secured in the desired position by tightening screws 69. This adjustment does not change the normal position of the pinion 33 which clears the gear 21 sufficiently to allow for slight variations in relation of the gear 21 to the flywheel housing; and this adjustment does not change the established relation of collar 34, lever 41, link 47 and solenoid armature 51 which is necessary to the transmission of force by the armature 51 axially to the link 47 at the outset of compression of spring 36 in the event of gear tooth abutment.

In place of the seal ring 70, a flexible rubber boot 100 (Fig. 7) can be used. The boot 100 has a peripheral bead 101 which fits snugly around the flange 61 of plate 60. The flange 61 is deformed to provide projections 102 (Fig. 10) which retain the bead. The central portion 103 of the boot has oblong holes 104 which receive the sides 46' of the yoke-shaped link 47' when it, together with the boot, are assembled with the armature 51 by the plate 49. The sides 46' have lugs 105 which engage the portion 103 of the boot when the armature 51 moves to the position shown in Fig. 8 to shift the pinion and close the solenoid switch. The boot is compressed by the lugs 105 so that the bead 101 is pressed against the plate 60 to provide a greater effective seal area as the armature 51 moves further into the solenoid housing. The lugs 105 limit relative movement between the boot and the sides 46' of link 47 so that wear of the boot is minimized.

While the embodiment of the present invention as herein disclosed, constitutes a preferred form, it is to be understood that other forms might be adopted.

What is claimed is as follows:

1. Engine starting apparatus comprising an electric motor having a shaft, a pinion connected with the shaft and movable axially into mesh with a gear of the engine to be started, a pivotally supported lever, a spring for transmitting to the pinion the motion of the lever which effects gear engaging movement of the pinion, a main switch for connecting the motor with the current source, means for effecting said motion of the lever and for closing said switch, said means com-

prising a solenoid having magnet windings and a linearly movable armature, a device for transmitting motion of the armature to the switch, a link for connecting the armature with the lever, said armature operating, when said windings are energized, to move the pinion into mesh with the engine gear and to close the switch and operating, in the event of abutment of the pinion teeth with the gear teeth, to deflect said spring while moving to close the main switch, a spring operating through the lever to retract the pinion from the gear, and a stop limiting the pinion-retractive movement of the lever to a position such that the pinion clears the gear and such that, in the event of tooth abutment, the link will be axially aligned with the solenoid armature when deflection of the first spring begins.

2. Engine starting apparatus comprising an electric motor having a field frame and a shaft, a pinion splinedly connected with the motor shaft and movable axially into mesh with a gear of the engine to be started, a solenoid for shifting the pinion and for connecting the motor with a current source and comprising an armature and an assembly which includes magnet windings, a switch having a movable contact and fixed contacts engaged thereby, a device which transmits movement of the armature to the movable contact to cause it to engage the fixed contacts, a spring which resists movement of the armature to close the switch and which by its deflection limits the movement of the armature in the switch closing direction, and a housing, a lever and a spring operable, when the windings are energized, to transmit motion from the solenoid armature to the pinion to shift the latter into mesh with the engine, said second spring yielding in the event of gear tooth abutment, to allow the solenoid armature to close the switch, a spring operating through the lever to retract the pinion, a stop limiting pinion-retracting movement of the lever whereby a definite normal relation between the solenoid armature and the motor frame is established, and means for attaching the solenoid housing to the motor field frame and providing for adjustment of said solenoid assembly therealong in order to vary the normal relation between the armature and said assembly in order to vary the amount of travel of the pinion when shifted by the armature.

3. Engine starting apparatus comprising an electric motor having a field frame and a shaft, a pinion splinedly connected with the shaft and movable into mesh with a gear of the engine to be started, a solenoid comprising an armature and an assembly which includes a housing into which a portion of the armature extends, said housing providing a support for axial movement of the armature, and which includes solenoid windings and a motor control switch actuated by the solenoid, means connecting the armature with the pinion, means for securing the solenoid housing to the motor frame and providing for adjustment of said housing therealong, and a cup-shaped, flexible rubber boot for enclosing the portion of the armature exterior to the housing and having its central portion connected with the armature and its peripheral portion connected with the housing, said boot permitting adjustment of the solenoid housing while the location of the armature remains unchanged.

JOHN E. ANTONIDIS.
